UNITED STATES PATENT OFFICE.

MYER DITTENHOEFER, OF NEW YORK, N. Y.

DESIGN FOR A MOUTH-PIECE FOR PIPES.

SPECIFICATION forming part of Design No. 15,552, dated November 18, 1884.

Application filed August 8, 1884. Term of patent 7 years.

To all whom it may concern:

Be it known that I, MYER DITTENHOEFER, a citizen of the United States, residing at New York, in the county and State of New York, have invented and produced a new and original Design for Mouth-Pieces for Pipes, of which the following is a specification, reference being had to the accompanying drawings, forming part thereof.

10 Figure 1 is a side elevation of my newly-designed mouth-piece, and Fig. 2 is a plan or top view of the same.

15 The object of my invention is to furnish a new and effective design for the embellishment of mouth-pieces for pipes; and the essential features consist, first, in a peculiarly ornamental lined surface, presenting, when viewed in elevation, the appearance of a matted, woven, or stippled surface; second, in an ornamental beaded edge; and, finally, in a beaded figure on the lower annular portion of the mouth-piece, all as will be fully set forth hereinafter.

20 Let *a*, in general, represent a mouth-piece for pipes which is of the usual oval shape in cross-section, except as to that portion termed the "saddle," and marked *b*, which is of an annular shape. The entire surface of the flattened portion of the mouth-piece, extending 25 from the tip *c* to the saddle *b*, except the edges thereof, is covered by fine lines, practically uniformly spaced, and running in opposite directions, crossing or interlacing with

each other, producing, when viewed as a whole, the effect of a matted, woven, or stippled surface, as seen at *d*. Both of the flattened sides of the mouth-piece are similarly ornamented. The lower portion, however, is left with a smooth surface to increase the ornate effect of the design. On each edge of the 30 mouth-piece is the longitudinal bead *e*, which extends from the tip part *c* the whole length thereof, and on the smooth-surfaced portion or saddle *b* are placed similar beads or ribs, *f*, transversely, which constitute, with the edge 35 beads *e*, a square or practically square outline. The tip portion *c* is left with a plain surface.

What I claim as new, and desire to secure by Letters Patent, is—

1. The design for mouth-pieces for pipes, 40 consisting of a mouth-piece having a matted or woven-like surface, and having a plain tip and plain saddle portion, as shown and described.

2. The design for mouth-pieces for pipes, 45 consisting of a mouth-piece having a matted or woven-like surface with beaded edges, substantially as shown and described.

3. The design described and shown, consisting of the matted-like surface *d*, beads *e*, and 50 beads *f*.

M. DITTENHOEFER.
